United States Patent Office

Des. 228,366
Patented Sept. 11, 1973

228,366

FONT OF ELECTRO-OPTICAL CHARACTERS

Brian Astle, Hightstown, N.J., assignor to Optel
Corporation, Princeton, N.J.

Filed Feb. 17, 1972, Ser. No. 227,334

Term of patent 14 years

Int. Cl. D18—04

U.S. Cl. D64—12 B

The figure on the drawing is a face view of a font of electro-optical characters illustrating my new design and showing the basic character together with the numerals formed therefrom as well as other embodiments for the numerals zero and seven employing the same basic character.

I claim:

The ornamental design for a font of electro-optical characters, as shown and described.
